(57) CLAIM

The ornamental design for a match striker, as shown and described.

DESCRIPTION

FIG. 1 is a perspective view of a match striker showing my new design.

FIG. 2 is a side view thereof.

FIG. 3 is a top view thereof; and,

FIG. 4 is a bottom view thereof.

The broken lines shown in the drawings depict portions of the match striker that form no part of the claimed design; in FIGS. 1-4, matches are shown in broken lines and form no part of the design.
